211,333

AUTOMOBILE ARM REST CONSOLE

Michael M. Graham, 2635 23rd St.,
Santa Monica, Calif. 90405

Filed Nov. 13, 1967, Ser. No. 9,354

Term of patent 14 years

(Cl. D14—6)

FIG.1.

FIG.2.

FIG.3.

4

4

FIG.4.

FIG.5.

FIG.6.

FIGURE 1 is a perspective view of an automobile arm rest console showing my new design;

FIGURE 2 is an end view of the front end thereof;

FIGURE 3 is a top plan view thereof;

FIGURE 4 is an end view of the rear end taken in the direction of the arrows 4—4 of FIGURE 3;

FIGURE 5 is a side elevational view thereof; and,

FIGURE 6 is a bottom plan view thereof.

I claim:

The ornamental design for an automobile arm rest console, substantially as shown.
